DISPLAY UNIT

Kenneth R. Platt, Prospect Heights, and Robert V. Sharp, Forest Park, Ill., assignors to Master Bronze Powder Company, Inc., Chicago Heights, Ill., a corporation of Indiana

Filed Sept. 24, 1968, Ser. No. 13,687

Term of patent 14 years

Int. Cl. D6—01

U.S. Cl. D80—9

FIG.1

FIG.3

FIG. 1 is a perspective view of a display unit showing our new and original design;

FIG. 2 is a front elevational view thereof, the rear and sides being the same as the front shown; and

FIG. 3 is a top plan view thereof, the bottom being plain.

We claim:

The ornamental design for a display unit, as shown and described.
